COLUMBIA PLANOGRAPH CO., WASHINGTON, D. C.

UNITED STATES PATENT OFFICE.

ZEBULUN R. HALL, OF OKFUSKEE, OKLAHOMA.

BACK-BAND ATTACHMENT.

1,090,146.

Specification of Letters Patent. Patented Mar. 17, 1914.

Application filed May 26, 1913. Serial No. 770,037.

To all whom it may concern:

Be it known that I, ZEBULUN R. HALL, a citizen of the United States, residing at Okfuskee, in the county of Okfuskee and State of Oklahoma, have invented a new and useful Back-Band Attachment, of which the following is a specification.

This invention relates to improvements in back bands.

10 An object of the present invention is to provide an improved form of back band which may be quickly adjusted according to the size of the draft animal with which the same is to be used.

15 A further object is to provide an improved form of back band which is readily adjustable and at the same time is so constituted that yielding stress brought to bear upon the securing buckle will be in alinement with

20 the holding strap thereof so that no tendency will be present which would tend to move the buckle and the holding strap thereof outwardly from the body portion to which the same is secured.

25 A further object is to provide a metallic end portion for the back band loop whereby wear due to the rubbing action of the chain or tug strap will be reduced to a minimum to thereby materially lengthen the life of

30 the various parts.

With the foregoing and other objects in view which will appear as the description proceeds, the invention resides in the combination and arrangement of parts and in the 35 details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

45 Figure 1 is a plan view of my improved back band. Fig. 2 is a longitudinal sectional view thereof.

Referring to the drawings in which similar reference numerals designate corresponding parts throughout the several views, 50 1 is the body portion of the back band preferably formed of leather or allied material and to the upper surface of which and adjacent the extremity thereof is secured the 55 adjusting member 2. The adjusting member 2 is secured at the four corners thereof to

the body portion 1 by rivets 6 or other equivalent means.

The adjusting member 2 is provided with a plurality of transverse slots 3 extending 60 for the majority of the distance thereacross and which slots define a plurality of ribs 12 above or beneath which extends the holding strap 4, the said slots 3 being of sufficient size for the accommodation of the holding 65 strap therein. One end of the holding strap is rigidly secured as at 121 to the body portion 1 from which it extends forwardly as at 13, is looped upon itself as at 14 and is interwoven between the various ribs 12 of the adjusting member 2 from which it passes rearwardly to be engaged by a buckle 5. The buckle 5 is provided with the usual holding 70 bar 9 and the locking member 10, which latter is adapted to engage one of a plurality of openings 11 with which the holding strap 4 is provided. The buckle 5 is held in place and with suitable rigidity by means of a strap 7 looped upon itself as at 8 which loop is adapted to receive the holding bar 9 75 of the buckle therein.

By the providing of the adjusting member 2 it prevents any tearing action to be brought upon the strap 7 which holds the buckle in place the only stress brought to 80 bear thereupon being in alinement with the longitudinal axis of the strap 7 which produces a shearing action upon the holding means therefor. Thus it will be apparent that there will be no tendency for the buckle 90 to be drawn outwardly from the body portion 1 for which the strap 7 and buckle 5 are not particularly adapted to resist.

In order to prevent excessive wear upon the loop 14 which is adapted to support the 95 chain 15 or a tug strap, the metallic member 16 is provided with slotted openings 17, through which the holding strap is adapted to extend. The metallic member 16 is formed of pliable metal or some material 100 which will successfully resist the wear of the rubbing action of the chain 15 thereon. The slots 17 of the said member define a raised rib 18 therebetween and beneath which the holding strap 4 passes. In order 105 to more rigidly secure the metallic member 16 to the loop 14 of the holding strap the lower portion thereof is provided with the raised rib 19 and the adjacent slots 20 through which the holding strap passes. 110

As illustrated in Fig. 2 of the drawings, the loop 14 may be formed at various in-

5 tervals along the adjusting member 2 so that a wide range of adjustment is obtained, the same being necessary when a single set of harness is to be used with draft 10 animals of different sizes. The dotted position illustrated in Fig. 2 shows the loop and the manner in which the metallic member is positioned therein. In order for the 15 loop 14 to be adjusted to the various intervals along the adjusting member 2, the free end 21 is first released from the locking member 10 of the buckle and the top portion of the strap withdrawn from beneath the various raised ribs 12. The metallic member is partially collapsed and the end 21 of the strap passes beneath a number of the ribs 12 so that the loop 14 of the metallic member is drawn bodily between the adjusting member 2 and the body portion 1. 20 When the desired point is reached the end 21 of the strap is passed outwardly through one of the slots 3 which therefore draws the metallic member to the position illustrated in dotted lines, after which the holding strap 25 is interwoven between the remaining ribs 12 and again securely fastened to the buckle 5, all of which it is thought will be readily apparent. Thus the number of adjusted positions depends solely upon the number of apertures 11 in the holding strap and the number of slots 3, it being pointed out that it is advisable to keep the loop 14 adjacent the portion 30 of the adjusting member from which it makes its exit.

35 The simplicity and wide range of adjustment of the back band herein described will be readily apparent and will render the device extremely important in those instances where a single set of draft harness 40 is to be used with a number of draft animals of different sizes.

Having thus described the invention what I claim is:—

1. In a back band, a body portion, an adjusting member provided with a plurality of transverse slots and rigidly secured to said body portion, a holding strap rigidly secured to the body portion and arranged to extend beneath the said adjusting member 50 and then outwardly through one of the

slots, and looped upon itself to form a retaining loop for the securing and holding of a tug strap or chain, and means arranged to adjustably engage the free end of the said holding strap. 55

2. In a device of the class described the combination of a body portion, an adjusting member secured thereto, said adjusting member being provided with a plurality of transverse slots, each slot extending nearly 60 across the said member, a holding strap rigidly secured to the said body portion and arranged to extend beneath the said adjusting member and to pass through one of the slots of the said adjusting member, said 65 strap being bent upon itself to form a tug holding loop, and a metallic member slidably secured to the said loop upon the inner portion thereof, said holding strap being interwoven between the slots of the said adjusting member, the free end of said strap being rigidly and adjustably secured to the body portion. 70

3. In a device of the class described, the combination of a body portion, an adjusting member rigidly secured thereto by means extending through the corners thereof, said adjusting member being provided with a plurality of transverse slots, each slot extending a greater part of the distance 80 thereacross, a holding strap rigidly secured to the said body portion, arranged to extend beneath the said adjusting member, looped upon itself and passing through one of the slots of the said adjusting member, said 85 holding strap being interwoven between the slots of the said adjusting member, a buckle rigidly secured to the said body portion and engaging the free end of the said holding strap, and a metallic member slidably and 90 adjustably secured to the inner portion of the loop of the adjusting member.

In testimony that I claim the foregoing as my own, I have hereto affixed my signature in the presence of two witnesses.

ZEBULUN R. HALL.
